ATTORNEY

UNITED STATES PATENT OFFICE.

JAMES CREIGHTON MATHEWES, OF LOS ANGELES, CALIFORNIA.

COIN COUNTER.

Application filed April 11, 1921. Serial No. 460,272.

To all whom it may concern:

Be it known that I, JAMES CREIGHTON MATHEWES, a citizen of the United States, residing at Los Angeles, in the county of Los Angeles and State of California, have invented new and useful Improvements in Coin Counters, of which the following is a specification.

My present invention has reference to a means for counting and wrapping coins.

My object is to provide a simple device in which the coins are received, adjustable means being arranged in the device on which the lowermost coin rests whereby a predetermined number of stacked coins, constituting the desired number to be counted and wrapped may be accurately determined.

The drawings illustrate a satisfactory embodiment of the improvement, and in which:—

Figure 1 is a perspective view of the improvement.

Figure 2 is a vertical longitudinal sectional view therethrough.

Figure 3 is a view showing the arrangement of the wrapper in the device, and coins of the number to be counted arranged in the wrapper.

Referring now to the drawings in detail, my improvement, in its entirety is broadly indicated by the numeral 1. The improvement includes a flat base 1 having a tubular extension in the nature of a sleeve 2. Secured to the base and projecting centrally through the sleeve 2 is a post 3. This post is centrally provided, from its upper end, with a threaded bore in which is received a screw 4 that has its outer end provided with a disk-like head 5.

Designed to rest on the upper edge of the sleeve 3 is the lower flanged end 6 of the coin receiving tube 7. The tube, at its outer end has a funnel-shaped extension 8 that provides the inlet for the tube. The funnel 8 is open at one of its sides, as at 9 which is of a width to permit of the insertion of the forefinger of the operator therethrough. At the juncture of the tube 7 with its funnel-shaped end 8, the opposed walls provided by the opening 9 are notched laterally as at 10.

The coins 11 are designed to be passed through the funnel mouth of the tube 7, the lowermost coin resting on the head 5 of the adjustable element or screw 4, and the uppermost coin, of the predetermined number of coins to be counted has its outer face flush

with the wall 12 which is in a line with the lower walls provided by the notches 10. The surplus coins, received in the funnel 8 are caused to be moved through the notches 10 by the finger of the operator exerting a pushing action against such coins.

Of course, the varying sizes of devices as

above described are provided for counting

varying denominations of coins, but in each

construction, the stacked coins will be

wrapped. To accomplish this, I provide tu-

bular wrappers 13. The wrappers 13 are of

the class ordinarily employed for the recep-

tion of coins and are of a length approxi-

mately equalling the length of the coin re-

ceiving tube 7 below the funnel-shaped

mouth 8 thereof. The tubular wrapper 13

is designed to rest on the base 1, the same

being received in the sleeve 2 and, of course,

surrounding the post 3. The tube 7 may be

arranged on the sleeve 2 either before or

after the wrapper is arranged in the sleeve

2 in contact with the base. The sleeve 13 has

its upper or outer end thus positioned a con-

siderable distance below the wall 12 and

the notches 10. The coins are fed through

the funnel into the wrapper and the surplus

coins as above stated, are moved by the

finger of the operator through the notches

10. When the outermost coin has its outer

face flush with the wall 12, the operator

presses his finger upon the said coin, grasp-

ing the funnel and turning the entire device

upside down. The base is now removed.

The operator's finger will hold the coins in

the tube, and a further pressure thereon will

move the coins bodily in the wrapper 13

a sufficient distance to allow the operator

to fold the projecting portion of the wrapper

over the uppermost coin. The operator

places his fingers on the folded end of the

wrapper, and inverts the tube, so that the

wrapper can be projected into the funnel

end of the tube, and the portion of the wrap-

per projecting beyond the uppermost coin

folded thereover, or the wrapper and coins

may be caused to slide through the bottom

of the tube and the end thereof closed after

being removed from the tube.

It is believed that the foregoing descrip-

tion, when taken in connection with the

drawings will fully set forth the construc-

tion and advantages of the improvement so

that further detailed description is not

deemed necessary.

Having described the invention, I claim:—

1. In a coin counting device, a base having an upstanding sleeve, a post on the base extending centrally through the sleeve, said post having a threaded opening, a screw engaging therein, a disk head for the screw, and a coin receiving tube having its lower end flanged and resting on the sleeve, as and for the purpose set forth.
2. A coin counting and wrapping device, comprising a base having an upstanding sleeve, a post on the base arranged centrally in the sleeve, an adjustable element on the post, a coin receiving tube having a lower flanged end to rest on the sleeve, a coin receiving wrapper of a length approximately equaling that of the tube received in the

tube and in the sleeve of the base for resting on the base to receive coins therein and whereby, when the finger of the operator is pressed upon the uppermost coin and the device is inverted and the base removed, the coins may be moved bodily by additional pressure from the finger of the operator to force the uppermost coin near the open outer end of the wrapper to permit of the wrapper being folded against said coin, and thereafter the wrapper and coins removed from the tube and the second open end thereof folded over the coins.

In testimony whereof I affix my signature.

JAMES CREIGHTON MATHEWES.
